United States Patent Office.

BENJAMIN C. TAYLOR, OF DAYTON, OHIO.

Letters Patent No. 67,609, dated August 6, 1867.

IMPROVEMENT IN HORSE-RAKES.

The Schedule referred to in these Letters Patent and making part of the same.

TO ALL WHOM IT MAY CONCERN:

Be it known that I, BENJAMIN C. TAYLOR, of Dayton, in the county of Montgomery, in the State of Ohio, have invented a new and improved Mode of Fastening Rake-Teeth in the Construction of Horse-Rakes; and I do hereby declare that the following is a full and exact description thereof, reference being had to the accompanying drawings, and to the letters of reference marked thereon.

The nature of my invention consists in a peculiar form of bracket fastening for the rake-teeth.

To enable others skilled in the art to make and use my invention, I will proceed to describe its construction and operation.

Reference is made to the annexed drawings marked B, and like letters of reference occurring on the different figures refer to like parts.

Figure 1 represents a perspective view of the fastening and its connection to the bar.

Figure 2 represents a transverse section of the same.

A represents the bar to which the fastening is attached, and B' the bracket fastening; C the tooth, having an eye formed by turning upwards, and D' the plate, which is enclosed within the flanged part and the plane surface beneath, and on the inner surface of this plate is a boss, with an orifice through it for the bolt, which, when the bolt is tightened, rests against the inner surface of the fastening. The transverse section, fig. 2, shows the relation of the several parts distinctly.

Having thus fully described my invention, what I desire to secure by Letters Patent, is—

I claim the bracket fastening B', constructed with one ear and a flange or housing extending from said ear in front and over the eye of the tooth, in combination with the washer D', substantially as and for the purpose described.

BENJAMIN C. TAYLOR.
